UNITED STATES PATENT OFFICE.

CHARLES C. SNODGRASS, OF PITTSBURGH, PENNSYLVANIA.

SPARK-PLUG.

1,341,221.

Specification of Letters Patent. Patented May 25, 1920.

Application filed March 5, 1919. Serial No. 230,706.

To all whom it may concern:

Be it known that I, CHARLES C. SNODGRASS, a citizen of the United States, and a resident of Pittsburgh, in the county of Allegheny and State of Pennsylvania, have invented a new and useful Improvement in Spark-Plugs; and I do hereby declare the following to be a full, clear, and exact description thereof.

10 My invention relates to spark-plugs for internal combustion engines.

The object of my invention is to provide a simple and durable form of spark-plug in which provision is made for taking care of 15 expansion and contraction which takes place under the higher temperature caused by the continual explosions taking place in the cylinder of the engine, thereby protecting the porcelains from cracking and causing a short-circuit. My improved spark-plug is particularly adapted for use in aeroplane engines subject to the sudden changes in temperature in passing from a low to a high altitude.

20 In the accompanying drawing, Figure 1 is an elevational view of my improved spark-plug; Fig. 2 is a longitudinal vertical sectional view, and Fig. 3 is an inverted plan view.

25 Referring to the drawing, the numeral 2 designates the outer shell or casing having the internal shoulder 3 which forms a support for the lower porcelain 4, a copper-gasket 5 being interposed between said shoulder 35 and the shoulder 6 formed on said porcelain.

Within the lower porcelain and cast integral therewith is the electrode-rod 7, said electrode-rod having at the lower end thereof the disk 8.

30 An aluminum gasket 9 surrounds the lower porcelain 4, and a castellated jam-nut 10 is screwed into the upper end of the casing 2 and locks said lower porcelain 4 securely within said casing 2. I prefer to use 45 a castellated jam-nut 10 as it may be screwed into place by an ordinary spanner which can be operated more conveniently and with less danger of breaking the porcelain than an ordinary wrench.

50 The upper porcelain 11 has the stud or projection 12, which enters the seat 13 in the upper end of the lower porcelain 4, and between the shoulder 14 of the upper porcelain 11 and the upper end of the lower porcelain an insulating washer 15 is interposed, said washer being formed of mica or other

suitable material. A space 16 is left between the lower end of the stud 12 and the bottom of the seat 13 to allow for expansion and contraction of the porcelains independently of each other.

55 The electrode-rod 7 passes up through the upper porcelain 11 and a knurled-nut 17 is screwed to the upper end of said electrode-rod.

60 A cap 18 fits over the top of the upper porcelain 11, and between said cap and knurled-nut 17 is the lock-nut 19.

The firing points 20 preferably made of tungsten steel are inserted through the walls 70 of the shell or casing 2 at a proper angle, said firing points being preferably three in number and properly spaced with reference to the disk 8, likewise preferably formed of tungsten steel.

75 The washer 15, interposed between the upper and lower porcelains, acts as a cushion to take care of expansion and contraction which takes place under the high temperature caused by the continual explosions taking place in the cylinders of the engine, thereby protecting the porcelains from cracking and causing short-circuit. As the expansion and contraction takes place rapidly above the shell 2, the upper porcelain 80 is more liable to break, especially in the case of aeroplane engines, where if a plane is flying low on a warm day, the porcelain becomes very hot, and where a sudden flight is made to a very high altitude, the temperature sometimes changes from 60° to 70°

85 F. to zero or below in a few minutes, and as the upper porcelain is exposed to the air currents. I have made provision for taking care of these sudden changes by forming the 90 upper porcelain separate from the lower, so that it can expand and contract independently of the lower porcelain. The lower porcelain inclosed as it is in the shell or casing receives more protection, and as the cold 100 air does not act directly upon it, it is not so liable to break, as the changes of temperature in the cylinder of the engine are not sudden.

95 The mica-disk or washer 15 also acts as a 105 cooling fin as the disk conducts the heat from the porcelain, and the cool air from the engine cooling fan carries off the heat from said disk, causing the temperature to remain low. The said disk 15 also may be termed 110 a high tension insulator, as it is impossible for the current to arc from the top of the

electrode-rod 7 to the shell or casing 2. Furthermore, said disk 15 acts as a water-shield which prevents the water from dropping on the lower porcelain, thereby keeping it dry and giving the current no path in which to travel to cause a short-circuit and resulting in the engine missing fire.

The disk 15 also affords the protection to the porcelain when putting the plug in or 10 removing it from the engine, for if the wrench should slip as it may often do, it will strike the disk first, thereby breaking the blow and saving the porcelain.

Another important feature of my invention is that both the upper and lower porcelains can be removed from the shell without unscrewing the shell from the engine cylinder. They are held firmly in place in the shell by the jam-nut 10 which forces the 20 porcelain down against the gasket 5 resting on the shoulder 3, pressure being applied to the conical shaped portion of the lower porcelain through the jam-nut 10 forcing the aluminum gasket 9 against said conical 25 seat.

What I claim is:

1. In a spark-plug, the combination of a suitable shell or casing, a lower porcelain supported therein, an upper and separate porcelain connected to said lower porcelain, 30 said upper porcelain being entirely above said shell or casing, and a disk of insulating material interposed between said porcelains and extending beyond the greatest diameter of said lower porcelain.

2. In a spark-plug, the combination of a suitable shell or casing, a lower porcelain supported therein, said lower porcelain projecting above said shell or casing, and having a recess formed therein, an upper and 40 separate porcelain having a projection entering said recess, and an insulating disk interposed between said porcelains.

In testimony whereof I, the said CHARLES C. SNODGRASS, have hereunto set my hand.

CHARLES C. SNODGRASS.
